CLAIM

The ornamental design for a data storage device as shown and described.

DESCRIPTION

FIG. 1 is a top front perspective view of a first embodiment of a data storage device showing the new design;
FIG. 2 is a front view thereof;
FIG. 3 is a rear view thereof;
FIG. 4 is a side view thereof;
FIG. 5 is another side view thereof;

FIG. 6 is a top plan view thereof; and
FIG. 7 is a bottom view thereof.

FIG. 8 is a top front perspective view of a second embodiment of a data storage device showing the new design,
FIG. 9 is a front view thereof;
FIG. 10 is a rear view thereof;
FIG. 11 is a side view thereof;
FIG. 12 is another side view thereof;
FIG. 13 is a top plan view thereof; and,
FIG. 14 is a bottom view thereof.

The data storage device is shown with a symbolic break in its thickness in FIGS. 1, 4-8, and 11-14. The break lines and any portion of the data storage device between the break lines form no part of the claimed design. All other broken lines depict portions of the data storage device that form no part of the claimed design. In the second embodiment, the dashed hatching applied to the oblique line pattern on the lower half of the data storage device represents a contrast in appearance only and is claimed.
